United States Patent Office.

LEWIS B. COVERT, OF CHICAGO, ILLINOIS.

Letters Patent No. 64,079, dated April 23, 1867.

IMPROVEMENT IN PAPER-FILES.

The Schedule referred to in these Letters Patent and making part of the same.

TO ALL WHOM IT MAY CONCERN:

Be it known that I, LEWIS B. COVERT, of Chicago, in the State of Illinois, have invented, made, and applied to use a certain new and useful Improvement in Paper-Files and Binders; and I do hereby declare the following to be a full, clear, and exact description of the said invention, reference being had to the annexed drawing, making part of this specification, wherein—

Figure 1 is a plan of my improved paper-file.

Figure 2 is a section at the line $z z$.

Figure 3 is a section at the line $y y$; and

Figure 4 shows the metal binding clasp and its washer detached.

Similar marks of reference denote the same parts.

My invention is a means for holding together newspapers, periodicals, letters, pamphlets, or similar articles, while in immediate use, and then attaching several together for filing away. I make use of a cover, of pasteboard or similar material, upon which are fastened one or more slides receiving the heads of perforating clasps. The sheets of paper are pressed upon these perforating clasps as they stand with the heads in the slides, and when the desired number of sheets has been added from time to time, they are clasped together by turning over the ends of the perforating clasps, and the book thus formed is slid out from the slides of the cover for filing away, and the cover can again be used by the introduction of other perforating points in the slides of the cover.

In the drawing, a represents a board or cover of any desired size or shape; b , slides made of sheet metal and secured to the cover by the ends $1 1$ being passed through and clinched. Several of these slides may be employed; I have shown two. $c c$ are my perforating clasps, made of sheet-metal strips, having at one end a point, split longitudinally as at 2, and at the other end a head formed of the metal strip folded together as at 3. This head is of a size to pass into the slide b .

In order to use this paper-file or binder, all that is necessary is to press the successive sheets upon the binder, so that the perforating clasps shall pass through them, and a cord of India rubber, e , may be employed to hold these sheets to their places as they are added from time to time. This elastic cord might be connected to small thimble pieces of wood or other material to cover up the projecting points of the perforating clasps. When the desired number of sheets has accumulated they are to be attached together by turning over or clinching the points of the clasps c , and I prefer that a washer or cap-plate, d , be first put upon the clasp. The book can then be drawn out and removed from the binder or file, and that be again used by introducing other perforating clasps into the slides b .

What I claim, and desire to secure by Letters Patent, is—

The file or binder formed of the cover a , and slides b , in combination with the perforating clasps c , as and for the purposes specified.

In witness whereof I have hereunto set my signature this twenty-fourth day of October, A. D. 1866.
